UNITED STATES PATENT OFFICE.

ROSALIA MOHR, OF SAN FRANCISCO, CALIFORNIA.

WINDOW AND SCREEN ATTACHMENT.

No. 814,468.

Specification of Letters Patent.

Patented March 6, 1906.

Application filed August 23, 1905. Serial No. 275,393.

To all whom it may concern:

Be it known that I, ROSALIA MOHR, a citizen of the United States, residing in the city and county of San Francisco and State of California, have invented new and useful Improvements in Window and Screen Attachments, of which the following is a specification.

My invention relates to screen attachments for slideable-sash windows.

It consists in a combination of parts and in details of construction, which will be more fully explained by reference to the accompanying drawings, in which—

15 Figure 1 is a partial vertical section showing the upper and lower parts of a window with my attachment. Fig. 2 is a section of the lower pocket with screen inclosed and lower rail of sash. Fig. 3 is an enlarged section of screen-joint and window-sash. Fig. 4 is a perspective view of the lower screen and pocket.

It is the object of my invention to provide vertically-slideable windows with screen attachments which may be readily engaged with or disengaged from the respective sashes and heads or pockets above and below the windows into which the screens are slideable and within which they are retained and concealed when not in use. Engaging and disengaging devices between the sashes and screens are provided, and means by which screens of greater longitudinal dimension than the pockets may be contained in such pockets.

35 A and B represent the upper and lower sashes, respectively, of a window. These sashes are slideable between the usual parting-strips and stops of the window-casing. In the head or upper part of this frame or casing 40 is formed a channel or pocket 2. This pocket stands in line with the inner edge of the top rail of the upper sash and is of sufficient size to admit the screen and its frame 3, which are vertically slideable and may be entirely concealed within the channel or may be withdrawn therefrom.

The screens and their frames may be made of metal or other material, the frames being preferably made thin, so as to occupy but little space.

45 In the top rail of the upper sash and close to its inner edge is made a small groove or channel, as at 4, in which the lower edge of the screen-frame may rest when the screen is withdrawn from its pocket, and thus when the sash is lowered the screen will follow it by

gravitation, and when raised the raising of the sash will also raise the screen.

When it is desired to move the window-sash without the screen, the latter is retained in its position by means of a spring 5, which is so attached that one angle will spring out beneath the lower edge of the screen-frame, and will thus retain it in place, so that the upper sash may be moved without dislodging the screen.

When it is desired to again release the screen, so that it may follow the sash in its movements, it is effected by means of a lug or spur 6, which is fixed to the upper rail of the lower sash, and by pushing the lower sash upward this lug engages that part of the spring 5 which is in line with the lug, pushing it to one side sufficiently to release the screen, the lower edge of which then rests upon the top of the closed upper sash and may be withdrawn with it. The lower sash can afterward be again pulled down to any desired position, and the upper screen will remain in connection with the upper sash until the latter is again pushed entirely up, when the screen will again be locked in place.

In line beneath the lower sash B is another pocket or channel 7, in which the lower screen 8 is slideable. As the location of these pockets is such that it is not always easy to provide a sufficient depth for the full length of the screen, I have shown the screen as formed in two parts 8 and 8^a. The meeting edges of the frames of these two parts are so formed that they interlock, as shown at 9, and these two-part screens are slideable with relation to each other, so that they may be closed up to occupy one-half or less, if desired, of the whole length of the screen. Thus when the screen is closed into its pocket 7 the lower edge of the bottom screen will first strike the bottom of the pocket. Then the upper portion of the screen will slide with reference thereto until the two are practically telescoped together.

10 is the window-sill, having its upper surface sloping downwardly and outwardly, and the inner edge may be slightly raised or upturned, as shown.

Upon the top of the upper portion 8^a of the lower screen is fixed a plate 11, having a similar inclination with the sill 10 and a lip adapted to overhang the upturned edge of the sill, thus forming a perfectly tight cover for the pocket 7 when the screens are lowered into place, and there will be little possibility of any entrance of rain, dust, or foreign matter.

In order, however, to provide for the escape of any moisture which may possibly enter or condense within this pocket, I have shown a discharge pipe or passage 12 opening downwardly and outwardly from the bottom of the pocket; thus providing an escape for any moisture, and, if desired, dust or other accumulation can be washed out through this passage.

10 In order to connect the upper screen 8^a with the bottom rail of the lower sash, I have shown a loop or staple 13 fixed to the top of the plate 11, and in the lower rail of the sash is pivoted an interlocking hook 14, the lower 15 end of which is adapted to engage the loop 13, and thus connect the two together. This hook is preferably so fulcrumed that it will operate by gravitation, and when the screens are within the pocket and the lower sash is 20 closed upon them the hook will engage, so that when the lower sash is again raised it will draw the screens or any desired portion of them up out of the pocket, thus making a complete protective connection with the sash 25 when it is opened.

The hook or connection 14 may be attached in various ways. In the present case I have shown it as pivoted with the top, and in order to disengage it from the screen when it is desired to open the window without withdrawing the screen I have shown a lug or button 15, projecting inwardly from the link 14, and this may be conveniently protected within a pocket, as at 16, fixed in a pocket in the lower 30 sash-rail and substantially flush with its inner face. This pocket is sufficiently large to admit the finger, and when it is desired to disengage the screen from the sash by pressing upon the button the hook will be pressed 35 backwardly sufficiently to disengage it from the loop, and the sash is then free to be raised without moving the screen.

Guide-strips 17 insure the alinement of the sections of the lower screen 8 8^a when they 40 are closed together or extended.

45 Having thus described my invention, what I claim, and desire to secure by Letters Patent, is—

1. The combination with a window-casing 50 and the sliding sashes, said casing having pockets made respectively above and below, of screens slidable so as to be concealed within said pockets, means for retaining one of the screens in its pocket, and means carried by 55 one of the sashes for tripping the retaining means to release the retained screen.

2. In a window, a casing having a pocket 60 in the upper part, a screen mounted in a frame and slidable in said pocket, a channel upon the top rail of the upper sash in which the lower edge of the screen-frame rests so as to be normally moved in unison with the sash,

and a member upon the casing adapted to project into the path of movement of the upper screen, for locking the screen within its 65 pocket and holding it suspended independent of said upper sash.

3. In a window, the casing having a head or pocket in the upper part, a screen slidable within said pocket and having its lower edge 70 adapted to normally rest upon and move with the upper sash, a latch whereby the screen is engaged and retained within its pocket and means for disengaging said latch to release the screen.

4. In a window, a casing having a pocket or channel in the top, a screen-frame slidable within said pocket, said screen-frame resting normally upon and movable with the sash an elastic latch adapted to engage and lock the 80 screen within its pocket when the upper sash is closed, a lug or projection carried by the upper rail of the lower sash so as to engage said spring and release the screen when the lower sash is raised for the purpose. 85

5. In a window, the combination of a casing having pockets at top and bottom, screens slidably mounted within said pockets, means whereby the screens may be detachably carried by the sashes to allow the screens to be 90 moved with the sashes or the sashes to be moved independently of the screens, and a member on the casing adapted to automatically project into the range of action of the upper screen-frame and thereby support said 95 screen-frame in its pocket independent of the upper sash.

6. In a window the combination with a casing having a sill with an upturned inner edge said casing having, also, a channel or pocket 100 made below the sill, of a screen-frame vertically movable into and out of the pocket and having at its upper end an inclined plate of greater width than the frame and of sufficient width to cover and extend each side of the 105 entrance to the pocket, one edge of said plate extending over the lip of the sill and turned downwardly over said lip to inclose the latter, and said plate having its opposite edge upturned and extended over the inclined portion of the plate and spaced therefrom to form an engaging loop, a hook member on the lower sash adapted to slide over the loop of said plate and to interlock therewith, and a push member carried by the hook member 110 to effect the disengagement thereof with the loop.

In testimony whereof I have hereunto set my hand in presence of two subscribing witnesses.

ROSALIA MOHR.
